CLAIM

The ornamental design for a personal computer, as shown and described.

DESCRIPTION

FIG. 1 is a perspective view of top, front and right side of a personal computer showing our new design;

FIG. 2 is a top plan view thereof;

FIG. 3 is a front view thereof;

FIG. 4 is a rear view thereof;

FIG. 5 is a left side view thereof;

FIG. 6 is a right side view thereof;

FIG. 7 is a bottom view thereof;

FIG. 8 is a cross sectional end view thereof taken along line 8—8 and shown omitting interior mechanism thereof;

FIG. 9 is a cross sectional end view thereof taken along line 9—9 and shown omitting interior mechanism thereof; and,

FIG. 10 is a perspective view with the lid in closed condition thereof.

Broken lines shown in the drawings illustrate portions of the personal computer, and form no part of the claimed design.
